UNITED STATES PATENT OFFICE

FREDERICK A. STRUCK AND ALBERT REINHARDT, OF DENVER, COLORADO

DESIGN FOR AN AUTOMOBILE TRUNK

Application filed August 1, 1931. Serial No. 40,757. Term of patent 14 years.

To all whom it may concern:

Be it known that we, FREDERICK A. STRUCK and ALBERT REINHARDT, both citizens of the United States, residing at Denver, in the county of Denver and State of Colorado, have invented a new, original, and ornamental Design for Automobile Trunks, of which the following is a specification, reference being had to the accompanying drawing, forming part hereof.

The drawing illustrates a perspective view of our new design.

The essential features of this design are the horizontal flat band which extends entirely around all four sides of the trunk a

substantial distance above the bottom thereof, together with the metallic beads which extend vertically from the aforesaid band on the front face of the trunk and across the lid thereof and the relation between the bands, beads, locks and handles of the trunk. The opposite end of the trunk, not shown, is similar to the end shown. The back of the trunk contains only the continuation of the flat, horizontal band.

We claim:

The ornamental design for an automobile trunk as shown and described.

FREDERICK A. STRUCK.
ALBERT REINHARDT.
